[57] CLAIM

The ornamental design for an electrical receptacle housing, as shown and described.

DESCRIPTION

FIG. 1 is a perspective view of an electrical receptacle housing showing my new design;

FIG. 2 is a front side elevational view thereof;

FIG. 3 is a top plan view thereof, the bottom view being identical;

FIG. 4 is a left side elevational view thereof, the right side being identical;

FIG. 5 is a rear side elevational view thereof;

FIG. 6 is a perspective view thereof shown attached to an electrical plug;

FIG. 7 is a perspective view of the receptacle housing showing a second embodiment of my new design having a semicircular groove therein;

FIG. 8 is a front side elevational view thereof;

FIG. 9 is a top plan view thereof, the bottom view being identical;

FIG. 10 is a left side elevational view thereof, the right side being identical; and,

FIG. 11 is a rear side elevational view thereof.

The broken line showing of the electrical plug in FIG. 6 and the electrical cords in FIGS. 1, 3, 4-7 and 9-11 together with the electrical contacts in FIGS. 1, 2, 7 and 8 is included for the purpose of illustrating environmental structure only and forms no part of the claimed design.
